CARPET GRIPPER

Harvey J. Hill, Monterey Park, Calif., assignor to Roberts Consolidated Industries, Inc., City of Industry, Calif., a corporation of California

Filed Aug. 27, 1965, Ser. No. 483,125

3 Claims. (Cl. 16—16)

ABSTRACT OF THE DISCLOSURE

A plywood carpet gripper strip having a laterally-outwardly-projecting upper flange under which the edge of carpeting may be tucked, and having a laterally-inwardly-projecting lower flange the upper surface of which is engageable by a padding trimming knife. This lower flange protects both the knife and a floor to which the gripper strip is attached.

Background of the invention

The present invention relates in general to carpet grippers for securing the edges of carpeting and, more particularly, to a gripper strip of the type having carpet hooking elements which project upwardly above the upper side or surface of the strip and which are inclined outwardly toward an outer edge of the strip to secure an edge of carpeting overlying the strip against inward movement relative to a room in which the carpeting is installed.

A gripper strip of the foregoing nature is ordinarily used with its outer edge adjacent, but spaced from, a wall in installing wall to wall carpeting. The raw edge of the carpeting is turned downwardly and tucked into the space between the wall and the outer edge of the strip to conceal it. Frequently, the outer edge of the strip is beveled downwardly and inwardly of the strip to provide additional space (for a given spacing of the strip from the wall) into which excess carpeting can be tucked, thereby reducing the precision with which the carpeting must be trimmed. (The spacing of the strip from the wall is preferably slightly less than the thickness of the carpeting so that the carpeting is compressed when the excess is tucked into the space between the strip and the wall. Such compression is necessary to resist unhooking of the carpeting under the influence of shuffling feet, shifting furniture, vacuum-cleaner suction, and the like.)

Normally, the carpeting is installed over padding with the edge of the padding more-or-less abutting the inner edge of the strip. This abutting relation is ordinarily attained by trimming the padding by running a knife along the inner edge of the strip as a guide, the point of the knife being in engagement with the floor adjacent the inner edge of the strip. With this procedure, an accurate fit between the gripper strip and the padding is achieved.

Summary and objects of the invention

A primary object of the invention is to provide a gripper strip of the foregoing general type wherein the configuration of the strip in cross section is such that more space is available between the outer edge of the strip and an adjacent wall (for a given spacing of the strip from the wall) to receive the corresponding edge of the carpeting, as compared to a strip having a beveled outer edge. This additional space reduces the accuracy with which the carpeting needs to be trimmed, which is an important feature. Another object in this connection is to provide the additional space mentioned with less wastage of the material of which the strip is made than is the case with the beveled outer edge mentioned.

2

Another primary object of the invention is to provide a gripper strip having a cross sectional configuration such that the inner edge of the strip may be used as a knife guide in cutting padding without engagement of the point of the knife with the floor. This construction eliminates scoring of the floor in the case of a wooden floor, or other floor surface capable of being scored, and minimizes the excessive dulling and wearing away of the point of the knife which is encountered when the floor is of concrete, or other hard material. When the inner edge of a conventional gripper strip is used as a knife guide for cutting padding on a concrete floor, the point of the knife must be sharpened frequently. The present invention minimizes the necessity for sharpening the knife, which is an important feature.

Considering the invention more specifically now, important objects are to provide an outer, upper flange extending longitudinally of the gripper strip and projecting laterally outwardly from the outer edge thereof and having an upper surface forming an outward extension of the upper side of the strip, and to provide an inner, lower flange extending longitudinally of the strip and projecting laterally inwardly from the inner edge thereof and having a lower surface forming an inward extension of the lower side of the strip.

The upper flange mentioned provides space therebeneath into which the edge of the carpeting may be tucked, thereby providing more carpet-receiving space between the outer edge of the strip and the wall than is available with the beveled outer edge hereinbefore discussed.

The gripper strip is preferably made of wood, or a similarly relatively soft and nonabrasive material, and the lower flange mentioned provides a knife-supporting surface which prevents scoring of the floor and/or excessive wear of the point of the knife when the knife is run along the inner edge of the strip in cutting the padding to fit.

Thus, the simple expedient of providing the strip with the upper and lower flanges mentioned attains the primary objectives of the invention with a very simple structure, which is an important feature.

A further object of the invention is to make the strip of three-ply plywood and to utilize portions of the upper and lower plies as the upper and lower flanges, respectively, the upper flange having a thickness substantially equal to the thickness of the upper ply and the lower flange having a thickness substantially equal to the thickness of the lower ply.

Another object is to minimize wastage of the plywood used to make the gripper strip of the invention by discarding only a small portion of the center ply between each pair of adjacent gripper strips.

The foregoing objects, advantages, features and results of the present invention, together with various other objects, features, advantages and results thereof which will be evident to those skilled in the art to which the invention relates, may be achieved with the exemplary embodiment of the invention described in detail hereinafter and illustrated in the accompanying drawing.

Description of the drawing

FIG. 1 is a fragmentary perspective view of a carpet gripper of the invention with padding overlying it in a position to be trimmed;

FIG. 2 is an enlarged sectional view, taken along the arrowed line 2—2 of FIG. 1, illustrating one way of trimming the padding in accordance with the invention;

FIG. 3 is a view similar to FIG. 2, but illustrating another way of trimming the padding in accordance with the invention; and

FIG. 4 is a view similar to FIGS. 2 and 3, but showing the padding after trimming and showing carpeting

which has been secured by the gripper strip with the raw edge of the carpeting tucked downwardly into an enlarged space provided by the invention.

Detailed description of the invention

The carpet gripper of the invention is designated generally by the numeral 10 and is shown secured to a floor 12 adjacent, but spaced from, a wall 14, as is conventional in any wall to wall carpeting installation. Preferably, the carpet gripper 10 is nailed to the floor 12, one nail being shown at 16 in FIG. 1, but it also may be secured in other ways, as by adhering it to the floor.

The carpet gripper 10 comprises a long, narrow, gripper strip 20 having upper and lower surfaces or sides 22 and 24 and outer and inner edges 26 and 28. The adjectives "outer" and "inner" are used herein with reference to the floor 12 being carpeted, the outer edge 26 of the gripper strip 20 being the edge thereof nearest the corresponding outer edge of the floor.

The carpet gripper 10 includes a plurality of carpet hooking elements 30 carried by the gripper strip 20 and projecting upwardly above the upper side 22 of the strip and inclined outwardly toward the outer edge 26 thereof to secure carpeting 32, FIG. 4, overlying the upper side of the gripper strip. Preferably, as is conventional, the gripper strip 20 is made of wood and the carpet hooking elements 30 are nails driven through the strip from the lower side 24 thereof. To prevent splitting, the gripper strip 20 is preferably made of plywood. In the construction illustrated, three-ply-plywood is used. More particularly, the gripper strip 20 comprises an upper ply 34, an intermediate ply 36 and a lower ply 38.

The upper ply 34 projects beyond the outer edge 26 of the gripper strip 20 and the lower ply 38 projects inwardly beyond the inner edge 28 of the gripper strip.

The effect is to provide the gripper strip 20 with an outer, upper flange 42 extending longitudinally of the strip and projecting laterally outwardly from the outer edge 26 thereof and having an upper surface forming an outward extension of the upper side 22 of the strip, and to provide the strip with an inner, lower flange 44 extending longitudinally of the strip and projecting laterally inwardly from the inner edge 28 thereof and having a lower surface forming an inward extension of the lower side 24 of the strip. The upper and lower flanges 42 and 44 may be formed with minimum wastage of the plywood sheet from which the gripper strip 20 is made.

For a given spacing of the outer edge of the upper ply 34 from the wall 14, the inward displacement of the outer edges of the intermediate and lower plies 36 and 38 resulting from the presence of the outwardly projecting upper flange 42 increases the volume of the space or gully 46 between the gripper strip 20 and the wall 14, as compared to conventional gripper strips wherein the outer edges of all plies are in the same vertical plane, or wherein the outer edge of the gripper strip is beveled so that the outer edges of the plies are in a plane sloping downwardly and inwardly. In the first instance, the additional gully volume is equal to the volume under the upper flange 42, and in the second instance, the additional volume is equal to one-half the volume under the upper flange.

The additional volume for the gully 46 which the present invention provides permits tucking a greater volume of the carpeting 32 into the gully after the carpeting has been stretched, hooked onto the carpet hooking elements 30, and trimmed, as shown in FIG. 4 of the drawing. Consequently, the operation of trimming the edge of the carpeting does not need to be carried out as accurately, which is an important feature of the enlarged gully 46 provided by the outwardly projecting upper flange 42 of the invention since it saves time in installing the carpeting 32.

Turning now to the inwardly projecting lower flange 75

44, it may be used as a support for a knife 50 employed to trim padding 52 by running the knife along the inner edge 28 of the gripper strip 20 with the point of the knife sliding along the upper surface of the lower flange 44. The knife may be positioned substantially vertically in trimming the padding 52, as shown in FIG. 2 of the drawing, or it may be inclined at an angle, as shown in FIG. 3 thereof. With the procedure shown in FIG. 2, the inner edge 28 of the gripper strip 20 is engaged by the side of the knife 50 to guide the knife. With the procedure of FIG. 3, the point of the knife is guided by the corner between the inner edge 28 of the gripper strip 20 and the upper surface of the lower flange 44.

In either case, any excess padding is trimmed off to provide a padding edge 54 which drops down into more-or-less abutting relation with the inner edge 28 of the gripper strip 20, as shown in FIG. 4 of the drawing. The padding edge 54 does not abut the inner edge 28 of the gripper strip 20 perfectly when the padding 52 is trimmed in this way, as will be clear from FIG. 4. However, precision fitting is not necessary since the padding 52 is soft and resilient and will readily conform to the slight irregularity provided by the power flange 44.

The inwardly projecting lower flange 44 has an extremely important function in that, by providing a wooden surface for the point of the knife 50 to slide along, it eliminates the rapid dulling and wearing away of the knife point which is normally encountered by sliding the point of the knife along a concrete floor in the absence of the lower flange 44. Thus, resharpening of the knife 50 is necessary only infrequently, as compared to conventional gripper strips without the lower flange 44 for protecting the point of the knife. Furthermore, in the case of a wooden floor, the presence of the lower flange 44 eliminates scoring of the floor.

Thus, the simple expedient of forming the gripper strip 20 with the upper and lower flanges 42 and 44 provides additional gully space (for a given spacing of the upper ply 34 from the wall) and provides protection for the knife 50 and the floor 12, all with a very simple structure, which is an important feature of the invention. It should be noted that the presence of the lower flange 44 permits increasing the gully space without increasing the spacing of the upper ply from the wall, and without any reduction in the strip width in contact with the floor, the latter being important to provide adequate resistance to the forces applied in stretching the carpeting.

Although an exemplary embodiment of the invention has been disclosed herein for purposes of illustration, it will be understood that various changes, modifications and substitutions may be incorporated in such embodiment without departing from the spirit of the invention as defined by the claims which follow.

I claim as my invention:

1. In a carpet gripper, the combination of:
  - (a) a long, narrow strip of wood having upper and lower sides and outer and inner edges;
  - (b) said lower side of said strip being engageable with a floor and said outer edge thereof being engageable by a downturned edge of carpeting overlying said upper side of said strip;
  - (c) an outer, upper integral flange extending longitudinally of said strip and projecting laterally outwardly from said outer edge thereof and having an upper surface forming an outward extension of said upper side of said strip;
  - (d) an inner, lower integral flange extending longitudinally of said strip and projecting laterally inwardly from said inner edge thereof and having a lower surface forming an inward extension of said lower side of said strip;
  - (e) said upper flange projecting laterally outwardly from said outer edge of said strip and said lower flange projecting laterally inwardly from said inner edge of said strip substantially equal distances so that

said strip is substantially symmetrical in cross section; and

(f) a plurality of carpet hooking elements carried by said strip and projecting upwardly above said upper side of said strip and inclined outwardly toward said outer edge of said strip to secure carpeting overlying said upper side of said strip.

2. A carpet gripper as defined in claim 1 wherein said upper and lower flanges project laterally outwardly and inwardly from their respective edges a distance less than the height of said strip.

3. A carpet gripper as defined in claim 1 wherein said strip is of three ply plywood, said upper and lower flanges being of a thickness at least equal to the thickness of their respective upper and lower plies.
